UNITED STATES PATENT OFFICE

OTTO ANDREAS ANDERSON, OF CHICAGO, ILLINOIS, ASSIGNOR TO ZANGERLE & PETERSON COMPANY, A CORPORATION OF ILLINOIS

DESIGN FOR A DAVENPORT OR LIKE ARTICLE

Application filed December 4, 1929. Serial No. 33,644. Term of patent 3½ years.

To all whom it may concern:

Be it known that I, OTTO ANDREAS ANDERSON, a citizen of the United States, residing at Chicago, Cook County, Illinois, have invented a new and ornamental Design for a Davenport or Like Article, of which the following is a specification, reference being had to the accompanying drawing, forming a part thereof.

port or like articles, showing my new design. The ornamentation shown is continued throughout the article.

I claim:

The ornamental design for a davenport or like article, as shown and described.

In witness whereof, I hereunto subscribe my name this 19th day of November, 1929.

OTTO ANDREAS ANDERSON.
